Patented 3rd May 1853.

James L. Jackson.

Grate frame. No. 3.

Aug 1853

James L. Jackson, of New York, N. Y.
Letters Patent No. 562 - Dated May 3rd 1853.

D562

The schedule referred to in these Letters Patent and making part of the same

To all whom it may concern:

Be it known that I, James L. Jackson, of the City, County and State of New York, have invented or produced, a certain new and original design for a grate frame, and I do hereby declare the following to be a full, clear and exact description of the same reference being had to the accompanying drawing, making a part thereof, and which represents one half of the frame complete - the other half which is the same in configuration, being shown in outline only, and representing by a sectional line the projections of the mouldings, &c.

The general form of the frame is straight sided with semi-circular top. The top centre piece is a human face a, in a shield from which springs out a vine b, wrought with arabesque foliage, and which vine gradually diminishes in size and swell until it terminates in a partially opened bud c. The foliage and vine overhangs a broad cavetto moulding d, underneath it, which in turn is margined by a bead e, and the ground between the foliage vine, &c, is open work. A sharp gothic bead encircles the ornaments, which runs into a broad concavo-convex moulding f, forming the outer margin of the frame.

The moulding f terminates in a long volute g, from the top of which is suspended a highly wrought fruit piece h, which completes the design.

The shaded line x, x, represents a section through the frame, showing the projections of the several parts thereof.

Having thus fully described the nature of my design, what I claim therein as new and desire to secure by Letters Patent, is the combination and arrangement of the figures, flowers, and ornaments herein represented, the whole forming an ornamental design for a grate frame.
